No. 826,393.

PATENTED JULY 17, 1906.

W. H. WHITE.
DRIER FOR ACETYLENE GAS.
APPLICATION FILED FEB. 26, 1906.

William Henry White,
Inventor.
B. & T. Seguin & Co.

UNITED STATES PATENT OFFICE.

WILLIAM HENRY WHITE, OF WATERBURY, CONNECTICUT.

DRIER FOR ACETYLENE GAS.

No. 826,393.

Specification of Letters Patent.

Patented July 17, 1906.

Application filed February 26, 1906. Serial No. 302,833.

To all whom it may concern:

Be it known that I, WILLIAM HENRY WHITE, a citizen of the United States, residing at Waterbury, in the county of New Haven and State of Connecticut, have invented a new and useful Improvement in Driers for Acetylene Gas; and I do hereby declare the following, when taken in connection with the accompanying drawings and the numerals of reference marked thereon, to be a full, clear, and exact description of the same, and which said drawings constitute part of this specification, and represent, in—

Figure 1, a view in side elevation of my improved gas-drier applied to an ordinary generator; Fig. 2, a detached plan view of the gas-drier; Fig. 3, a view thereof in vertical section; Fig. 4, a detached sectional view of the bottom plate; Fig. 5, a detached broken sectional view of the lower end of the inside shell, showing the bayonet-joint groove formed therein; Fig. 6, a detached sectional view of the guard-tube.

My invention relates to an improved gas-drier for use in drying acetylene gas, the object being to produce a simple, convenient, and effective device for removing from acetylene gas all traces of the moisture associated with it as it leaves the generator.

Although primarily designed to be used as an attachment for generators carried for lighting purposes on automobiles, my improved gas-drier may of course be used in any situation where such a device is needed.

With these ends in view my invention consists in a gas-drier having certain details of construction and combinations of parts, as will be hereinafter described, and pointed out in the claims.

For the better illustration of my improved device I have shown it in conjunction with a generator which may be regarded for my present purpose as typical of the entire class and consisting of a water-tank 2, connected by pivoted coupling-rods 3 and thumb-nuts 4 with a case 5, containing a carbid-chamber 6, an ash-receiving chamber 7, and a screen 8, separating these chambers. A perforated tube 9, entering the chamber 6, receives water from the tank 2 through a pipe 10, controlled by a valve 11, whereby the water is fractionally supplied from the tank 2 through the pipe 10 and perforated tube 9 to the carbid-chamber 6.

The generator above described is such a generator as is carried by automobiles for the generation of the gas required for lighting. As herein shown, my improved gas-drier is constructed with particular reference to being applied to one of the two coupling-rods 3 of the generator. It may, however, be attached thereto in any other way, or, if preferred, it may have no connection therewith other than through the tubes through which it receives the gas to be dried and enriched therefrom. As shown, the drier is provided with two nipples 12 for the application of two tubes 13, leading to them from corresponding nipples 14, located upon the top of the tank 2. However, one tube and one nipple on the drier and one tube and one nipple on the generator will suffice. The said nipples 12 are located upon the opposite faces of a cap 15, which is internally threaded for being screwed upon the threaded upper end of a tube 16, which I shall hereinafter call the "gas-supply" tube. Ports 17 in the cap 15 register with corresponding ports 18 in the upper end of the said tube 16, into which the gas is thus led from the nipples 12. The said tube 16 is encircled near its upper end by a washer 19, which might, of course, be made integral with the tube and form an annular flange. This washer 19 is set down flush into a circular plate 20, to which it is secured by brazing or otherwise, whereby the tube is secured in place. The plate 20 is set into the upper end of a cylinder or outer shell 21, in which it is screwed or with which, if preferred, it may be made integral, the said plate and shell forming what, for convenience, I shall call the outer "case" or "body" of the device. This outer case or body is, in effect, a cup turned bottom up.

The gas fed into the tube 16 passes out through perforations 22 in its lower end into a guard-tube 23 larger in diameter than it is. This guard-tube has perforations 24 in its lower end and secured by soldering or otherwise to the center of a perforated diaphragm 25, which divides the inner shell or cup 26 into a carbid-chamber 27 and an ash-chamber 28, this cup being formed, as shown, with a shoulder 29 for the diaphragm 25 to rest upon. Also, as shown, the guard-tube 23 is closed at its lower end by a bottom plate 30; but this may be made integral, if preferred. The lower end of the shell 26 is closed by a

removable bottom plate 31, having concentric flanges 32 and 33 upon its upper face. The said flange 32 is adapted in diameter to fit snugly within the shell 26, to which the 5 plate is removably secured by a bayonet-slot lock comprising a small projection 34, struck out from the flange and coacting with a shallow groove 35, formed in the inner face of the lower end of the shell 26. To permit the 10 plate to be turned as required for removing it from and replacing it in the shell, it is provided with a depending finger-piece 36. The flange 33 is formed with external threads taking into corresponding threads in the lower 15 end of the shell 21, whereby the plate 31, and hence the cup of which it forms a part, is secured to the case or body of the device. The upper edge of the shell comes to a bearing upon a packing 37, placed against the inner 20 face of the plate 20. The upper end of the guard-tube 23 also comes to a bearing upon this packing. The upper end of the shell 23 is formed with holes 38, leading into an annular chamber 39, formed between the shells 21 and 26. From this chamber the gas enters a 25 nipple 40, containing a strainer 41. If preferred, of course, the device may be provided with two or more nipples like the nipple 40. As shown, also, the shell 21 is provided with 30 straps or clips 42, by means of which the device is mounted upon the coupling-rod 3. After the carbid-chamber 26 has been filled with carbid and the cup of the device is restored to the body thereof the guard-tube 23 35 sleeves over, as it were, the gas-supply tube 16, which is thus protected from the carbid. But for the guard-tube the gas-supply tube would have to force its way through the carbid, which would be likely to clog its openings 22.

In the operation of the device the gas generated in the generator passes from the nipples 12 into the gas-supply tube 16, from 45 which it passes into and through the guard-tube 23 and thence into the carbid-chamber 27, charged with carbid, which having a very great affinity for moisture extracts the same from the gas, which it leaves perfectly dry. The dry gas then passes through the perforations 38 in the shell 26 into the chamber 39 and thence through the nipple 40, from which 50 it is conducted in any convenient way to the lamps. The moisture extracted by the carbid from the gas slowly decomposes it with the production of a small quantity of acetylene gas, which is added to the volume of gas going through the drier. As the carbid is 55 decomposed its powdery ashes drop through the diaphragm 25 into the chamber 28, from which they are removed by the removal of the doubly-flanged bottom plate 31. The 60 operation of my improved drier is virtually the straining of acetylene gas through carbid, which extracts from it its moisture, which in

turn decomposes the carbid with the production of more gas.

It is apparent that in carrying out my invention my improved gas-drier may assume a variety of different forms, the object being to produce a gas-drier to be used in conjunction with a gas-generator and to contain carbid which not only extracts the moisture from the gas, but also swells it in volume. I would therefore have it understood that I do not limit myself to the exact construction herein shown and described, but hold myself at liberty to make such departures therefrom as fairly fall within the spirit and scope of my invention.

I claim—

1. In a gas-drier, the combination with a case open at the bottom, of a cup entered into the case through the open bottom thereof, a diaphragm located in the said cup forming a carbid-chamber and an ash-chamber, a 85 guard-tube located in the carbid-chamber, and a gas-supply tube extending downward from the top of the case into the guard-tube, the said cup and case being constructed for the exit of the dried gas from the carbid-chamber.

2. In a gas-drier, the combination with a case open at the bottom, of a cup entered into the case through the open bottom thereof and smaller in diameter than the same, forming an annular gas-chamber between them, a diaphragm located in the cup forming the carbid-chamber and an ash-chamber, a guard-tube located in the carbid-chamber and having passages opening thereinto, and a gas-supply tube leading downward into the guard-tube from the top of the case and opening into the guard-tube, the said case and cup being constructed for the exit of the dried gas from the carbid-chamber.

3. In a gas-drier, the combination with a case open at the bottom, of a cup entered into the case through the open bottom thereof and smaller in diameter than the same forming an annular gas-chamber between them, a diaphragm located in the cup forming a carbid-chamber and an ash-chamber, a guard-tube located in the carbid-chamber and opening thereinto, a gas-supply tube leading downward into the guard-tube from the top 115 of the case and opening into the guard-tube, the said case and cup being constructed for the exit of the dried gas from the carbid-chamber, and a removable bottom plate for the said cup.

4. In a gas-drier, the combination with a case open at the bottom, of a cup entered into the case through the open bottom thereof, its upper edge forming a joint with the lower face of the top of the case, a diaphragm located in the cup forming a carbid-chamber and an ash-chamber, a guard-tube supported by the said diaphragm and extended upward.

in the carbid-chamber to form a joint with the lower face of the top of the case, a gas-supply tube extending downward from the top of the case into the guard-tube, and 5 means for supplying gas to the gas-supply tube and for the exit of the dried gas from the carbid-chamber through the case.

In testimony whereof I have signed this specification in the presence of two subscribing witnesses.

WM. HENRY WHITE.
